DEFINITE POLE ALTERNATOR

Leroy H. Palmer, Bell, Calif.

Application March 7, 1936, Serial No. 67,664

6 Claims. (Cl. 171—252)

This invention relates to a definite pole alternator.

Such alternators in general have been in common use for a long time. They usually involve a stationary armature and a rotating field structure, excited by direct current. Difficulties in the design of such alternators are inherent when the problem of regulation is considered. As the load increases, the armature reaction increases; and its effect in turn depends upon the power factor. This reaction results in a modification of the effective field magnetism, and there is usually a decided drop in the generated electromotive force as the load increases. It has been customary in the past to provide some means for compensating for this drop, which can be operated to vary the field excitation.

It is one of the objects of this invention to reduce very materially the effect of this armature reaction and thereby to ensure good regulation of the electromotive force between no load and full load without the necessity of varying the field excitation.

This object is attained by special reference to the design of the field spider and of the air gap. In the past it has been almost universal to employ relatively large gaps in an attempt to reduce armature self-induction. It has been found however, on actual tests, that an alternator built in accordance with this invention, and in which the air gap is very small can be operated with very little reduction in the electromotive force at full load. It is believed that this effect is due to the very low magnetic reluctance in that path which includes the pole pieces, as compared with the path intermediate the pole pieces.

Accordingly, it is another object of this invention to provide a definite pole alternator in which the magnetic circuit is designed to provide a magnetic reluctance through the pole pieces that is very low as compared with a path intermediate the poles.

This invention possesses many other advantages, and has other objects which may be made more easily apparent from a consideration of one embodiment of the invention. For this purpose there is shown a form in the drawing accompanying and forming part of the present specification. This form shall now be described in detail, illustrating the general principles of the invention; but it is to be understood that this detailed description is not to be taken in a limiting sense, since the scope of this invention is best defined by the appended claims.

Referring to the drawing:

Figure 1 is a front elevation of an alternator embodying the invention, some of the parts being broken away and a part of the rotating field structure being in section;

Fig. 2 is a vertical sectional view taken along the plane 2—2 of Fig. 1; and

Fig. 3 is a detail section illustrating the manner of attaching the pole pieces to the revolving field structure, as seen along the plane 3—3 of Fig. 1.

In the present instance, the armature core 1 is shown as being made up of a series of laminations and appropriately supported by a frame 2. This frame 2 has the end housings 3 and 4, provided with feet 5. The shaft 6 is appropriately supported as by ball bearings, in the housings 3 and 4. The armature winding 7 is indicated in diagrammatic fashion only.

The field structure is supported upon the shaft 6 by the aid of a spider or hub 8, which may be pressed onto the shaft 6. This spider 8, as well as the pole pieces 9, can be formed of appropriate magnetic material such as mild steel, either cast or forged. Such mild steel may be of low carbon content, such as 20 points of carbon.

In the present instance the alternator is shown as having six poles. Each of the pole pieces is surrounded by a field coil 10. Excitation for the field can be obtained by way of the collector rings 12 and brushes 13 in the conventional manner.

Each of the pole pieces 9 can be provided with a pole tip 11 having an arcuate exterior surface. One of the important features of this invention resides in the fact that the air gap between the pole tip 11 and the armature structure 1 is of very low value; of the order of 2½ or 3 thousandths of an inch per inch of radius of the revolving field.

The manner in which the individual pole pieces 9 are fastened to the spider or hub 8 is such that a very low magnetic reluctance is provided at the joints. For this purpose, each of the pole pieces 9 may be provided with an inwardly radially extending projection 14. These projections fit very snugly into corresponding radial recesses 15 formed in the hub or spider 8. In order to lock the pole pieces in place, a transverse locking pin 16 can be used, which passes transversely across the recesses 15 and through the projections 14. These locking pins are preferably made of low magnetic reluctance material, and should have a tight fit in the apertures provided therefor.

Surrounding each of the projections 14 there is a shoulder 17 on each of the pole pieces 9. This shoulder contacts snugly with the corresponding

surface of the spider 8, which is formed with flat sides for this purpose.

It is seen that the area of contact between each of the pole pieces 9 and the corresponding area on the hub 8 is made quite large, and an intimate contact is provided by accurate machining of the flat surfaces and of the cylindrical surfaces forming the projection 14 and the recess 15. In this way, a very low magnetic reluctance is provided for the magnetic path through a pair of adjacent pole pieces and the intermediate portion of the hub 8. By providing the small air gap as defined above, in conjunction with this low reluctance, it has been found that the problem of regulation is avoided; and tests have shown that from no load to full load conditions the generated electromotive force does not vary by more than a few percent.

Apparently the armature core structure and the field core structure cooperate to reduce the inherent effects of the armature reaction upon regulation.

What is claimed is:

1. In a definite pole alternator, an armature having a magnetic core, and a field structure cooperating with the armature and having a magnetic core, said field core having a series of pole pieces as well as a hub support for the pieces, said hub support and pole pieces being joined by a radial projection extending from one of the elements into a closely contacting recess formed in the other element, there being a shoulder surface formed around the projection in intimate contact with the corresponding surface on the other element, to provide a tight joint at these surfaces, and the air gap between the pole pieces and the armature being of the order of two thousandths of an inch to three thousandths of an inch per inch of radius of the rotating element.

2. In a definite pole alternator, an armature having a magnetic core, and a field structure cooperating with the armature and having a magnetic core, said field core having field-pole pieces forming an air gap with the armature core of the order of two-thousandths of an inch to three-thousandths of an inch per inch of radius of the rotating element, said field core having a hub provided with radial recesses, and the pole pieces having projections closely contacting substantially all surfaces of the recesses, said pole pieces also having a shoulder surface around the projections in intimate contact with the corresponding hub surfaces; said field core also having locking means extending across the recesses and through the projections and made from magnetic material, to hold the contacting surfaces in intimate relation to each other.

3. A definite pole alternator having an armature core structure as well as a magnetic field structure with a central element and definite pole pieces attached thereto, one of the structures being rotatable, characterized by the fact that the air gap between the structures is reduced to a value of the order of two and one half thousandths of an inch per inch of radius of the rotating structure, and that the magnetic reluctance through the magnetic path including the pole pieces is further reduced to a very low value by ensuring a large and intimate contact between the pole piece surfaces that contact with the central element.

4. A definite pole alternator having an armature core structure as well as a magnetic field structure with a central element and definite pole pieces attached thereto, one of the structures being rotatable, characterized by the fact that the air gap between the structures is reduced to a value of the order of two and one half thousandths of an inch per inch of radius of the rotating structure, that each of the pole pieces and the central element are joined by the aid of a projection telescoping into and closely contacting substantially all surfaces of a corresponding recess, and that there is a shoulder surrounding the projection in intimate contact with the corresponding surface on the other element.

5. In an alternator, an armature core structure, and a field core structure, one of said structures being rotatable, said field core structure having definite pole pieces and a hub supporting said pieces, the air gap between the structures being of the order of three thousandths of an inch per inch of radius of the rotating structure, and each of said pole pieces being joined to the hub so as to form large contacting surfaces between the pole piece and the hub and held in close contacting relation to each other for reducing the magnetic reluctance through the definite pole structure.

6. In an alternator, an armature core structure, and a field core structure, one of said structures being rotatable, said field core structure having definite pole pieces and a hub supporting said pieces, the air gap between the structures being of the order of three thousandths of an inch per inch of radius of the rotating structure, and each of said pole pieces being joined to the hub by a radial projection extending into a closely contacting recess, there being a shoulder surface formed around the projection and urged into intimate contact with the corresponding surface.
